UNITED STATES PATENT OFFICE.

MONCKTON W. MICHELL, OF FANWOOD, NEW JERSEY.

DESIGN FOR A BOTTLE.

SPECIFICATION forming part of Design No. 15,620, dated December 16, 1884.

Application filed October 27, 1884. Term of patent 3½ years.

To all whom it may concern:

Be it known that I, MONCKTON W. MICHELL, a citizen of the United States, residing in Fanwood, in the county of Union and State of New Jersey, have invented or produced a new and original Design for Bottles, of which the following is a specification.

My design is shown in the two views of the accompanying photograph, of which Figure 1 is a perspective front view, and Fig. 2 a perspective diagonal view.

The bottle has, in general, the form of the frustum of a slender right pyramid of square base. This general form is varied by means of horizontal moldings, a projecting base, and other ornamentalations, and the whole is surmounted by a cylindrical cap with dome-shaped top.

Let *a* designate the square projecting base, *b* a pyramidal frustum mounted thereon, and *C*, as a whole, the main pyramidal frustum mounted thereon and extending thence to the flat top *d*. Around the frustum *C*, near its top and bottom, respectively, are two horizontal moldings, *e* and *f*, along the upper sides of which are a series of teeth or angular projections, as shown. Of the four faces of the frustum *C* between these moldings *e* *f* three are ornamented, as shown in Fig. 1, with a roughened ground, against which is a design, *g*, in low relief, consisting of two series of parallel horizontal lines, with vertical lines connecting them in pairs, the whole somewhat suggestive of a row of pilasters resting on a continuous base and upholding an entablature. The fourth side has a plain ground ornamented by raised lettering. The lower frustum, *b*,

is ornamented by means of horizontal lines in low relief, interrupted by a design, *h*, on the middle of each side, consisting of two pairs of vertical lines, with a horizontal line extending over them, surmounted by inclined lines, as shown. On the flat top is mounted a cylindrical cap or button, *I*, having a swelled or convex top. Around its cylindrical side is a band or stripe of close vertical lines.

A bottle made according to my design presents a unique, harmonious, and attractive appearance.

What I claim as new and patentable is as follows:

1. The design for a bottle, substantially as shown in the accompanying photographs.

2. The design for a bottle, consisting of a frustum of a slender square-based pyramid mounted on a square projecting base and traversed by serrated moldings, as shown.

3. The design for a bottle, consisting of a frustum of a slender square-based pyramid mounted on a projecting base traversed by serrated moldings and ornamented with designs *g* and *h* in lines, as shown.

4. The design for a bottle, consisting of a frustum of a pyramid mounted on a projecting base traversed by horizontal moldings and surmounted by a cylindrical cap, as shown.

In witness whereof I have hereunto signed my name in the presence of two subscribing witnesses.

MONCKTON W. MICHELL.
